Des. 237,595
Patented Nov. 11, 1975

237,595

MEASURING TAPE

Edward Meissner, Fort Lee, N.J., assignor to Cooper
Industries, Inc., Houston, Tex.

Filed Apr. 22, 1974, Ser. No. 463,049

Term of patent 14 years

Int. Cl. D10—04

U.S. Cl. D10—72

FIG.1

FIG.2

FIG.4

FIG.3

FIG.5

FIG.6

FIG.7

FIG. 1 is a top perspective view of a measuring tape showing my new design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front side elevational view thereof; and

FIG. 7 is a rear side elevational view thereof.

I claim:

The ornamental design for a measuring tape, as shown and described.
